DANIEL KELLEHER, OF SANDUSKY, OHIO, ASSIGNOR TO THE HINDE & DAUCH PAPER COMPANY, OF SANDUSKY, OHIO, A CORPORATION OF OHIO.

METHOD OF SCORING PAPER BLANKS

1,196,956.

Specification of Letters Patent. Patented Sept. 5, 1916.

Application filed October 16, 1914. Serial No. 866,993.

To all whom it may concern:

Be it known that I, DANIEL KELLEHER, a citizen of the United States of America, residing at Sandusky, in the county of Erie 5 and State of Ohio, have invented certain new and useful Improvements in Methods of Scoring Paper Blanks, of which the following is a specification, reference being had thereto to the accompanying drawings.

10 The invention relates to the manufacture of scored paper blanks such as are used in the construction of paper boxes and similar articles, and it is the object of the invention to obtain a method of scoring which is less 15 injurious to the stock, and which may be more quickly performed than the methods heretofore employed.

In the drawings: Figure 1 illustrates a side elevation of an apparatus used for 20 scoring by my improved method; Fig. 2 is a cross section thereof; Fig. 3 is a cross section through a scored blank when removed from the machine and bent in one direction; and Fig. 4 is a similar view showing the 25 blank bent for folding in the opposite direction.

In the present state of the art it is usual to score cellular paper blanks by pressing a scoring blade against one side of the blank 30 and against an abutment on the opposite side, thereby crushing down the cellular structure. The operation is also performed in some cases by scoring disks between which the blank is fed and which similarly crush 35 down the cellular structure. Scores formed by either of the methods above described permit the blank to be folded in one direction, but a bending in the reverse direction will stress the material so as to endanger 40 breaking. With my improved method the score is formed by moving a tongue member at an angle into a groove member, the action being progressive from one end of the score to the other and so gradual as to permit the 45 stock to be drawn around the bend without undue stress. This is preferably accomplished by forming the tongue member in the cross section of a traveling belt and the groove member in the cross section of an adjacent traveling belt, the two belts being in slightly angular relation to each other so 50 that the tongue is in full engagement at one

end and enters into engagement at the opposite end.

As shown in the drawings, A is an endless belt running over pulleys B, and of a cross section shown in Fig. 2, in which C is a projecting tongue. D is a similar endless belt running over pulleys E and of a cross section having a groove F for receiving the 60 tongue C and beveled portions G on opposite sides of said groove. The two belts are so driven that their adjacent strands are traveling in the same direction, and as indicated in Fig. 1 these strands are in slightly 65 angular relation to each other. Thus, when a cellular blank is fed in between the belts at the open end it will be fed along and the material will be progressively pressed downward by the tongue portion C into the 70 groove portion F. The gradual and progressive operation will permit the drawing in of the material longitudinally of the blank to compensate for the bend and without any stress which might turn the paper. 75 The bevel portions G will also press the material in the reverse direction, producing the reverse bends or scores.

Another feature of my improvement is the scoring of the blank in such a manner as to 80 draw the paper forming the crease equally from both sides of the blank. It will be observed that by reason of the bevels G on opposite sides of the grooved portion F, the length of the paper on one side of the blank 85 is substantially equal to that on the other side. In other words the scored portion is so fashioned that neither side of the paper blank is placed under a tension greater than that on the other side, and consequently the 90 stock is not weakened.

What I claim as my invention is:—

1. The method of scoring cellular paper blanks, comprising the simultaneous creasing of the stock along parallel lines and 95 toward opposite sides to form a section flexible in opposite directions.

2. The method of scoring cellular blanks, comprising the simultaneous and longitudinally progressive creasing of the material 100 along parallel lines and toward opposite sides of the stock to form a section flexible in opposite directions.

3. The method of scoring cellular blanks,

comprising the placing of the stock between opposite tongue and groove members, and the progressive pressing of said members into engagement from one end to the other of the blank.

4. The method of scoring cellular paper blanks consisting in feeding the stock between adjacent members moving in rectilinearly converging paths, one of which

members has a tongue progressively entering the stock to form a crease.

In testimony whereof I affix my signature in presence of two witnesses.

DANIEL KELLEHER.
